(57) **CLAIM**

The ornamental design for a fishing rod holder, as shown and described.

DESCRIPTION

FIG. 1 is a perspective view of a fishing rod holder showing my new design;

FIG. 2 is an additional perspective view thereof, with the broken line disclosure of fishing poles being for illustrative purposes only and forming no part of the claimed design;
FIG. 3 is an enlarged perspective view of one of the leg mechanisms thereof, with the remainder of the holder being omitted for clarity of illustration;

FIG. 4 is an enlarged perspective view of one of the foot assemblies thereof, with the remainder of the holder being omitted for clarity of illustration;

FIG. 5 is an enlarged elevational view of one of the foot assemblies thereof, with the remainder of the holder being omitted for clarity of illustration;

FIG. 6 is an additional enlarged elevational view of one of the foot assemblies thereof, with the remainder of the holder being omitted for clarity of illustration; and,

FIG. 7 is a perspective view thereof, shown in a collapsed configuration.
